(57) **CLAIM**

The ornamental design for a work bench, as shown and described.

DESCRIPTION

FIG. 1 is a perspective view of a work bench showing my new design; with the grip articles attached to the work surface and legs shown in partially extended position;

FIG. 2 is a perspective view thereof; with the grip articles removed for clarity and legs shown in partially extended position;

FIG. 3 is a perspective view thereof; with the work bench shown in a folded position;

FIG. 4 is a top plan view of FIG. 3;

FIG. 5 is a bottom plan view of FIG. 3;

FIG. 6 is a left side elevational view of FIG. 3;

FIG. 7 is a right side elevational view of FIG. 3;

FIG. 8 is a rear elevational view of FIG. 3;

FIG. 9 is a front elevational view of FIG. 3;

FIG. 10 is a top perspective view of the work bench; shown in an expanded position with legs in their contracted position;

FIG. 11 is a top perspective view of FIG. 10; shown in a partially expanded position;

FIG. 12 is a top plan view of FIG. 10;

FIG. 13 is a left side elevational view of FIG. 10;

FIG. 14 is a right side elevational view of FIG. 10;

FIG. 15 is a rear elevational view of FIG. 10;

FIG. 16 is a front elevational view of FIG. 10; and,

FIG. 17 is a bottom perspective view of FIG. 10.
